UNITED STATES PATENT OFFICE.

REUBEN BROOKS, OF GLOUCESTER, MASSACHUSETTS.

COLLAPSIBLE TUBE.

943,234.

Specification of Letters Patent. Patented Dec. 14, 1909.

Application filed March 3, 1909. Serial No. 481,184.

To all whom it may concern:

Be it known that I, REUBEN BROOKS, of Gloucester, in the county of Essex and State of Massachusetts, have invented certain new and useful Improvements in Collapsible Tubes, of which the following is a specification.

This invention relates to a collapsible tube which is charged with a liquid or semi-liquid material, such as glue, paint, etc., the tube having a delivering end through which its contents are forced in a stream by compressing pressure on the walls of the tubes when the latter is in use.

15 The invention also relates to a tube of this character which, when put upon the market, has an incipient outlet closed by a puncturable wall or septum, the tube being accompanied by a pointed plug adapted to penetrate the septum, thus completing and filling the outlet.

20 The invention has for its object, first, to provide a tube of this character with means for smoothly spreading the stream of liquid into a thin strip having clearly defined edges, the strip being of a predetermined width.

25 The invention also has for its object to enable the depth or thickness of the deposited strip of material to be regulated or varied by varying the inclination of the tube with reference to the surface on which the material is deposited by it.

30 The invention further has for its object to provide improved means for laterally supporting the plug when it is inserted in the outlet of the tube, and preventing it from being tipped in such manner as to enlarge or distort the outlet.

35 To these ends the invention consists in the improvements which I will now proceed to describe and claim.

Of the accompanying drawings, forming a part of this specification.—Figure 1 represents a side view of the delivering end portion of a collapsible tube embodying my invention. Fig. 2 represents an end view of the same. Fig. 3 represents a section on line 3—3 of Fig. 1. Fig. 4 represents a view similar to Fig. 3, showing a penetrating plug engaged with the outlet end of the tube. Fig. 5 represents a sectional view of the delivering end portion of the tube in operation. Fig. 6 represents a sectional view 55 of a modification.

The same reference characters indicate the same parts in all the figures.

In the drawings.—12 represents the body portion of a collapsible tube which is preferably seamless and made of a suitable flexible metal or alloy, one end of the tube being suitably closed by flattening it and folding the flattened parts together after the tube has been charged. I have not shown this portion of the tube as my invention does not relate thereto, but relates instead entirely to the delivering end portion of the tube. Said delivering end portion is preferably of conical form, and is provided at its apex with a circular cavity 13 extending from the outer surface partly to the interior of the tube, said cavity being separated from the interior of the tube by a penetrable septum 14 formed of the same material as the tube, and adapted to be ruptured by the pointed 75 plug hereinafter referred to, the cavity 13 constituting the outer end of an outlet, the inner end of which is formed by the rupturing of the septum 14. The tube is placed upon the market with the septum 14 intact, 80 so that the tube has no outlet until one is provided by the user by the aid of the penetrating plug.

15 represents the plug which is made of cylindrical wire, the diameter of which is 85 substantially equal to that of the cavity 13, one end of the plug being sharpened so that it is adapted to penetrate the septum 14, and thus complete the outlet of the tube.

16 represents a rigid projection which is 90 formed on the apex of the delivering end of the tube, and is integral therewith, the projection being formed from the material of the tube by a suitable molding or pressing operation. The main portion of the 95 projection is at one side of the cavity 13, the inner side of the projection being preferably provided with a groove or recess 17 which is in alinement with one side of the cavity 13, so that when the plug 15 is inserted in the outlet, it has an extended bearing on that part of the projection which is formed by the groove 17. The projection 100 is provided with a beveled or inclined face 18 at the opposite ends of which are ears or 105 runners 19 which have curved edges and project somewhat above the upper edge of the face 18. When the tube is inverted and applied to the surface 20 to which the contents of the tube are to be applied, the run- 110

ners 19 bear upon said surface and by reason of their projection above the outer edge of the face 18, hold said face slightly separated from the surface 20. When pressure is exerted on the tube to force a stream of its liquid contents through the outlet, said stream is deposited on the surface 20 between the runners 19, and is spread by the outer edge of the spreading face 18. The runners 19 bearing on said surface limit the spreading of the stream and cause the same to be deposited in a thin strip or ribbon of uniform width having sharply defined edges. The form of the runners is such that the acting edge of the spreading face 18 may be raised or lowered relatively to the surface by varying the inclination of the tube while it is in use, thus varying the thickness of the strip or ribbon of liquid material applied to the surface 20. This will be understood by reference to Fig. 5, where the tube is shown with its longitudinal axis slightly inclined relatively to the surface 20. By increasing the degree of inclination of the tube, the acting edge of the face 18 will be brought nearer to the surface 20, thus reducing the thickness of the applied strip, which is indicated at 22 in Fig. 5.

The projection 16 is further utilized as a means for supporting the plug 15, and preventing the latter from being laterally displaced or tipped to enlarge or distort the outlet opening. As before stated, the groove or recess 17 in the inner side of the projection constitutes an elongated bearing for one side of the plug 15, thus preventing the tipping of the plug toward the side of the outlet occupied by the projection. Any suitable provision may be made for preventing the tipping of the plug in the opposite direction. I have here shown the plug provided with a finger 23 formed to bear on the outer side of the projection 16, and engage a notch or recess 24 formed therein. Provision is thus made for preventing the plug from tipping away from the projection, and also from being accidentally dislodged from the outlet. The finger 23 is an extension of the wire blank of which the plug 15 is made, the wire being preferably coiled to form a head or loop 25.

In Fig. 6, I show the above described im-

provement embodied in an internally threaded cap adapted for engagement with an externally threaded neck or nozzle 26 at 55 the delivering end of a collapsible tube 12. The said cap has a base portion 27 which is internally threaded to engage the nozzle 26, the outer portion of the cap being provided with the cavity 13, projection 16, and runners 19, all formed and relatively arranged substantially as above described.

I claim:

1. A collapsible tube having an outlet, and a projection at one side of the outlet, 65 the outer end of said projection being formed to spread and limit the width of a stream of liquid issuing from the outlet.

2. A collapsible tube having an outlet, and a projection on its delivering end at one side 70 of the outlet, said projection having a stream spreading face and runners located at opposite ends of said face and projecting above the same.

3. A collapsible tube having an outlet, 75 and a projection on its delivering end at one side of the outlet, said projection having a stream spreading face and runners located at opposite ends of said face and projecting above the same, the runners being formed to 80 vary the height of the acting edge of the spreading face above the surface on which the runners bear.

4. A collapsing tube having a delivering end provided with a cavity which is separated from the interior of the tube by a puncturable septum, and a rigid projection on the said end at one side of the cavity, said projection being formed to engage and laterally support a pointed plug adapted to 90 penetrate the septum and engage the projection.

5. A collapsible tube having a projection on its delivering end at one side of its outlet combined with a plug having a finger adapted to engage the outer side of said projection, the body of the plug bearing on the inner side of the projection.

In testimony whereof I have affixed my signature, in presence of two witnesses.

REUBEN BROOKS.
